Primary Examiner — Jasmine Mlinarcik*Assistant Examiner* — James P McKane(74) *Attorney, Agent, or Firm* — Oppenhuizen Law PLC; David L. Oppenhuizen(57) **CLAIM**

The ornamental design for a disposable medical gown, as shown and described.

DESCRIPTION

FIG. 1 is a rear view of a disposable medical gown showing the new design;

FIG. 2 is a front view thereof;

FIG. 3 is a rear view thereof as worn by a user in an open configuration;

FIG. 4 is a rear view thereof as worn by a user in a closed configuration; and,

FIG. 5 is a rear perspective view thereof as worn by a user in a closed configuration.

The broken lines in FIGS. 3-5 representing portions of the human form and showing the gown in use form no part of the claimed design.

The surface shading is intended to depict surface contour and forms no part of the claimed design.
